(57) **CLAIM**

(52) U.S. Cl. **D8/307**

We claim the ornamental design for knob and escutcheon portions of a thumb turn latch, as shown and described.

(58) **Field of Search** .... D8/300, 307-312, D8/320, 339, 338, 341; D23/250-4; 292/336.3, 347, 356, 357, DIG. 12, DIG. 30, DIG. 37; 16/110.1, 412-417, 419, 438, 441, 443

DESCRIPTION

(56) **References Cited**

FIG. 1 is perspective view of knob and escutcheon portions of a thumb turn latch showing our new design;

U.S. PATENT DOCUMENTS

FIG. 2 is a front elevational view thereof, on an enlarged scale;

- D. 435,781 * 1/2001 Freck D8/338
2,585,643 * 2/1952 Feldman 70/81
4,014,573 * 3/1977 Lehnoff 292/347
5,027,629 * 7/1991 Liu .
5,265,454 * 11/1993 Crocco et al. 70/380
5,586,796 * 12/1996 Fraser 292/357

FIG. 3 is a top plan view thereof; and,
FIG. 4 is a right side elevational view thereof, it being understood that the left side view is a mirror image of the right side view.

The broken-line disclosure of elements of a thumb turn latch is provided for illustrative purposes only and forms no part of the claimed design.
